UNITED STATES PATENT OFFICE.

GEBHARD C. BOHN, OF ST. PAUL, MINNESOTA.

REFRIGERATOR.

Application filed February 23, 1928. Serial No. 89,962.

My invention relates to improvements in refrigerators, and particularly to that type of refrigerator wherein an ice chamber is positioned at one side of a refrigerating compartment, the refrigerating compartment extending under the ice chamber, and with an openwork, vertical partition between the refrigerating compartment and ice chamber, and a passageway through the bottom of the ice chamber to permit circulation from the refrigerating compartment through the ice chamber and back into the refrigerating compartment.

I have, heretofore, in constructing this form of refrigerator, made the refrigerating compartment preferably of a one-piece construction, coated with enamel by an enameling process requiring the application of intense heat, with the ice chamber compartment of non-enamed construction. It is, in a refrigerator of this kind, particularly desirable to have the interior coated with this form of enamel, but there have been many difficulties to overcome in having both the refrigerating compartment and ice chamber coated with this form of enamel and at the same time be without the objectionable features of seams or cracks, into which the odors can pass and bring about a source of contamination.

An essential object of the present invention is the securing of a construction in which both the refrigerating compartment and the ice holding compartment may be coated with this form of enamel before being placed in the refrigerator frame-work, and when placed together in the refrigerator frame-work will be secured together in a convenient and efficient manner and without cracks that will absorb any contaminating odors.

A further object of my invention consists of improvements in the construction of the ice chamber compartment that will protect the refrigerating compartment against sweating and leakage from the ice chamber compartment, and bring about a dry circulation of air from the ice to the refrigerating compartment, with the maximum protection of the contents of the refrigerating compartment.

These and other features of my invention will appear more fully in the accompanying description and drawings and will be more particularly pointed out in the claims.

In the drawings representing my invention:

Figure 1, is a view in transverse vertical section through an assembly of refrigerating and ice chamber construction in accordance with my invention. 60

Figure 2, is a view in isometric perspective of an ice chamber unit with air current deflection plates shown therein in dotted lines.

Figure 3, is a view in transverse section taken approximately on a line 3-3 of Figure 2. 65

Figure 4, is a view in isometric perspective of the cutaway upper portion of the refrigerating compartment lining unit with which the ice chamber shown in Figures 2 and 3 70 interlocks.

Figure 5, is a view in front elevation of the structure shown in Figure 4.

Figure 6, is a view in top elevation and transverse section, respectively, of an insulating unit which is mounted beneath the floor of the ice chamber. 75

Figure 7, is a view in isometric perspective of a refrigerator embodying the invention, a portion of the ice chamber door being broken away to show the interior of the ice chamber. 80

Figure 8, is a fragmentary sectional view on the line 8-8 of Figure 1, and

Figure 9, is a view in front elevation of so much of the structure as is illustrated in 85 Figure 8.

Referring to the drawings, A represents the refrigerating compartment lining, and B the ice chamber lining of the compartment. Each of these compartments is constructed in the form of a box-like seamless sheet metal chamber coated with vitrified enamel before being placed in the refrigerator framework, the refrigerating compartment A being so constructed as to form a support for the ice chamber compartment, and the chambers being constructed to interlock and placed in position within the refrigerator framework in the manner more particularly hereinafter set forth. The refrigerating compartment, as shown particularly in Figure 1, is of box-like shape to constitute the inner wall of the refrigerator with its upper right hand corner cut away to interlockingly receive the ice chamber. 95

A shelf 1 is integrally connected to the rear wall of the refrigerating compartment at the cut away portion and extends forwardly therefrom, the right hand edge 29 of said shelf being spaced inwardly from the adjacent side wall of the refrigerating compartment. The side wall 38 of the refrigerating 105

105

110

- compartment extends upwardly an appreciable distance above the level of said shelf, and is provided with inturned end portions 2 and 3, extending inwardly and connected with the shelf 1. The forward edge of the shelf 1 is formed with a downturned flange 4, and the forward edges of the compartment A, such as the edge 5 (see Figure 4), are turned inwardly to make curved, sanitary corners. 10 The inner edge 30 of the shelf 1 is bent upward and the top thereof is curved inward and downward to house an insulating strip 6, as of wood.

An opening 7 is provided in the shelf 1 to provide for the passage of a drain pipe 8 therethrough. The top wall of the compartment A is formed with an upturned edge flange 9 to interlock with the downturned edge flange 10 of the ice chamber B, as shown 20 in Figure 1. The vertical rear edge 11 of the compartment A overlaps the vertical rear edge 12 of the ice chamber B and is connected thereto by means of bolts 13 passing through the metal strip 39, said metal strip forming an end support for the deflecting plates 14, said metal strip 39 thus covering the joint caused by the overlapping edges 11 and 12.

The ice chamber compartment B comprises 30 a rear wall 15, a vertical side wall 16, a top 17, and a bottom 18, an inwardly turned flange 19 being provided about the front thereof to form a rounded, sanitary corner. The lower portion of the side wall 16 is bent inward at 35 20 and then backward upon itself and then upwardly, as shown in Figure 3, forming a housing for an insulative unit 22, preferably of wood, which is slidably inserted in the housing thus formed. The inner side of the 40 bottom of the ice chamber is upturned to engage the overturned edge of the shelf 1 of the refrigerating compartment. The upturned edge 31 aids in holding the insulating member 6 in place and coacting with the overturned edge of the shelf 1 to form a substantially water tight seal therewith. The ice chamber B is formed with a forward wall 23 extending across the front of said chamber and of the same height as the front and rear 45 portions 2 and 3 of the refrigerating compartment wall A. The lower edge of the wall 23 extends downward below the bottom 18 of the ice chamber to form a sealing flange across the space between the bottom 18 of the 50 ice chamber and the shelf 1. Upon the shelf 1 is placed an insulative unit 24 preferably formed of wooden slats 25, having a covering of water proofed felt 26 and 27 upon opposite sides thereof. A notch 28 is cut in 55 the forward end of the insulative unit through which the drain pipe 8 passes.

The outer edge 32 of the ice chamber bottom is bent up and over to interlockingly engage the upturned edge flange 29 of the 60 shelf 1 to form a water tight joint prevent-

ing water from the ice chamber flowing into the refrigerating compartment below the ice chamber. The inwardly folded lower portion 21 of the ice chamber extends inwardly over the bottom of said chamber, so that water falling on said portion 21 will be deflected thereby onto the bottom 18 of the ice chamber, instead of flowing down into the refrigerating compartment beneath the ice chamber. 70 The front of the refrigerating compartment 75 is open to provide for the door openings. The refrigerating compartment is constructed without any front wall so as to provide for the usual door construction. The front edges of the ice chamber and refrigerating compartment are connected with the front wall of the refrigerator housing in the usual manner. The deflecting plates 14 are supported at their rear ends by the metal strip 39 and are supported at their other ends in a desired 80 manner on the front wall of the refrigerator between the ice chamber door and the refrigerating compartment door 37.

A removable rack of ordinary type is preferably laid on the floor of the ice chamber 90 to support a supply of ice and prevent injury to the ice chamber floor.

In carrying out my invention, I first construct the refrigerating compartment and ice chamber, as separate, one-piece units, whereby they may each be coated on their inner sides with vitrified enamel, which is baked thereon under intense heat, whereby each compartment is without joints or cracks that will absorb odors or be subject to chipping. 95 I then place the refrigerating compartment within the refrigerator housing, securing it at its edges to said housing in the usual manner. The ice chamber is then positioned within the cutaway portion of the refrigerating compartment with the intermediate insulating strips 6 and 24 in position, and the insulating unit 22 positioned within the water deflecting ledge 20, and the ice chamber and refrigerating compartment interlocked through the medium of the flanges 9 and 10. The deflecting plates, with their supporting end strips 39, are then placed in position, as shown in Figure 1, with the rear end strip 39 covering the overlapping edges 11 and 12 of the refrigerating compartment and ice chamber, the bolts 13 passing through said strip and through said overlapping edges 11 and 12. Thus, the only joints in the vertical walls of the interlocked refrigerating compartment and ice chamber are covered by the strip 39. By means of the construction described I overcome the difficulties that have been encountered in the attempt to secure a vitrified enamel unit form of both ice chamber and refrigerating compartment, and obtain a construction with respect to the ice chamber, as well as the refrigerating compartment, that will stand the intense heat generated in the enameling process without 100 105 110 115 120 125 130

warping and being distorted; that is easy to assemble, and when assembled is of the maximum sanitary efficiency through the absence of joints, cracks, or seams, that would absorb 5 the odors and be subject to chipping at exposed edges.

I further provide improved features of construction in connection with the insulated joining of the ice chamber and refrigerating 10 compartment below the ice chamber, and between the side of the ice chamber and the side portion of the refrigerating compartment below the deflecting plates, preventing the injurious effects to the food contents caused by 15 sweating from ice within the ice chamber. I, also, by means of the features of construction shown and described, carry off all the water that collects within the ice chamber without any of said water being permitted to 20 pass from the ice chamber into the refrigerating compartment.

The insulated deflecting ledge 20 further cooperates in preventing sweating and, together with the particular form of insulating 25 of the bottom floor of the ice chamber, forms a resilient support for the ice within the chamber.

The functioning of my refrigerator, when assembled, is the same as takes place in ordinary 30 refrigerators of the same general type shown in the drawings, wherein the air in the refrigerating compartment passes between the deflecting plates into the ice chamber and around the ice and around the inner 35 edge of the bottom of the ice chamber into the refrigerating compartment below the ice chamber, a constant circulation being maintained by means of which the refrigerating compartment is kept cooled by the circulating air passing over the ice in the ice 40 chamber.

An important advantage of my invention lies in the structural independence of the ice chamber and refrigerating compartment with 45 cooperating means for joining together and sealing the two compartments when placed in position. This structural independence of the refrigerating compartment and ice chamber permits ice chambers of different 50 grades of construction being used and a selected one being placed in connection with the refrigerating compartment, and permits a convenient removal and placing in position of the ice chamber without interfering with 55 the refrigerating compartment.

While the features of invention described are particularly adapted for use in a construction wherein both the refrigerating compartment and the ice chamber are 60 enameled, it is not my intention herein to limit myself to the use of my features of invention only with ice chamber and refrigerating compartments of the enameled character.

I claim:

65 1. A refrigerator lining, comprising a uni-

tary refrigerating compartment, a separate unitary ice chamber supported within said compartment and above the bottom of the same, the meeting vertical edges of said compartment and ice chamber overlapping, a 70 partition wall separating said refrigerating compartment and ice chamber, a supporting end of said partition wall covering the overlapping edges of said refrigerating compartment and ice chamber, and means securing said supporting end of the partition wall to and through said overlapping edges of compartment and chamber.

2. A refrigerator lining, comprising a unitary refrigerating compartment, a separate 80 unitary ice chamber positioned within one side of said compartment and above the bottom of the same, the vertical meeting edges of said compartment and ice chamber overlapping, a ported partition wall separating said refrigerating compartment and ice chamber and secured over the overlapping edges of said compartment and chamber.

3. A refrigerator lining, comprising a refrigerating compartment having a cutaway 90 upper side portion and an inturned horizontal wall at the bottom of said cutaway portion, a unitary ice chamber positioned in the cutaway portion of said refrigerating compartment and supported upon said horizontal wall, and an interlocking connection between said refrigerating compartment and ice 95 chamber.

4. A refrigerator lining, comprising a unitary refrigerating compartment having a 100 cutaway upper side portion and an inturned horizontal wall constituting the bottom of said cutaway portion, a unitary ice chamber removably supported within said cutaway portion, with the bottom wall of the ice chamber separated from the horizontal wall, and an insulating unit filling the space between 105 said horizontal wall and the bottom wall of the ice chamber.

5. A refrigerator lining, comprising a 110 unitary refrigerating compartment, formed with an upper side cutaway portion and a horizontal wall at the bottom of said cutaway portion, said horizontal wall having an upturned connecting wall adjacent the interior 115 of the refrigerating compartment, a unitary ice chamber removably secured within the cutaway portion of said refrigerating compartment with a bottom wall conforming to and separated from said horizontal wall of the refrigerating compartment and the upwardly extending vertical extension of said horizontal wall, and insulating units filling the space between the bottom of said ice 120 chamber and said horizontal wall and the vertical extension of said horizontal wall.

6. A refrigerator lining, comprising a refrigerating compartment having an upper side cutaway portion and a horizontal imperforate wall forming the bottom of said cut- 130

- away portion, a unitary ice chamber, means removably supporting said ice chamber within the cutaway portion of said refrigerating compartment, said ice chamber having an imperforate wall separated from said horizontal wall, an insulating unit filling the space between the bottom of said ice chamber and said horizontal wall, and drainage means passing downwardly through said ice chamber bottom, said horizontal wall, and the intermediate insulating unit.
7. A refrigerator lining, comprising a unitary refrigerating compartment having an upper side cutaway portion and a horizontal imperforate wall forming the bottom of said cutaway portion, a unitary ice chamber positioned within the cutaway portion of said refrigerating compartment and formed with an imperforate bottom spaced from said horizontal wall, an insulating unit filling the space between said ice chamber and said horizontal wall, interlocking connections between the bottom of said ice chamber and said horizontal wall and between the body portions of said chamber and refrigerating compartment, a ported vertical partition separating said refrigerating compartment and ice chamber, an inwardly directed ledge carried by the outer wall of said ice chamber and extending over the ice chamber bottom with an outlet air port between said ledge and ice chamber bottom, and drainage means passing through the imperforate bottom of said ice chamber and insulating unit and the horizontal wall below said ice chamber bottom.
8. A refrigerator lining, comprising a unitary refrigerating compartment having an upper side cutaway portion and an imperforate horizontal wall constituting the bottom of said cutaway portion, a unitary ice cham-

ber removably supported within the cutaway portion of said refrigerating compartment and formed with an imperforate bottom interlocking with and separated from said horizontal wall, an insulating unit between said ice chamber bottom and said horizontal wall, a ported vertical partition wall separating said refrigerating compartment and ice chamber, a hollow deflecting ledge projecting inwardly from the outer wall of said ice chamber, said ledge projecting over the adjacent end of the ice chamber bottom and separated therefrom to form an outlet air port, and an insulating unit filling said ledge.

9. A refrigerator lining, comprising a unitary refrigerating compartment, a separate unitary ice chamber supported in one side and above the bottom of said refrigerating compartment, and an interlocking wall engagement between said refrigerating compartment and ice chamber whereby the exterior walls of the ice chamber, in co-operation with the corresponding walls of the refrigerating compartment, constitute a continuous lining.

10. A refrigerator lining, comprising a unitary refrigerating compartment, a separate unitary ice chamber supported in one side and above the bottom of said refrigerating compartment, an interlocking wall engagement between said refrigerating compartment and ice chamber whereby the exterior walls of the ice-chamber, in co-operation with the corresponding walls of the refrigerating compartment, constitute a continuous lining, and a multiple ported division wall between said ice chamber and refrigerating compartment.

In testimony whereof I affix my signature.
GEBHARD C. BÖHN.
